UNITED STATES PATENT OFFICE.

CHRIS LARSON, OF DENVER, COLORADO, ASSIGNOR OF ONE-HALF TO HENRY C. OHLMAN, OF DENVER, COLORADO.

ENGINE.

1,126,035.

Specification of Letters Patent.

Patented Jan. 26, 1915.

Application filed March 18, 1914. Serial No. 825,576.

To all whom it may concern:

Be it known that I, CHRIS LARSON, a citizen of the United States, residing at Denver, in the county of Denver and State of Colorado, have invented certain new and useful Improvements in Engines, of which the following is a specification.

My invention relates to certain new and useful improvements in vapor actuated engines of the type in which the intake and exhaust of motive fluid at opposite ends of a reciprocating piston is controlled by valves which are mounted on the piston.

My invention relates more particularly to engines of the type in which the valves are automatically shifted during and by the reciprocating movement of the piston on which they are mounted, to admit and exhaust the motive fluid alternately at opposite sides of the piston, and its primary object resides in the provision of certain improvements which simplify the construction of an engine of this character, while rendering its operation more reliable and effective.

Another object of my invention resides in the provision of improved means by which the positions of the valves can be reversed at any point in the movement of the piston to reverse the direction of rotation of the crank shaft with which the piston is operationally connected.

An embodiment of my invention has been illustrated in the accompanying drawings in the various views of which like parts are similarly designated, and in which,

Figure 1 is a longitudinal, axial section through the cylinder and piston of the engine, Fig. 2, a section taken along the line 2—2, Fig. 1, Fig. 3, a section along the line 3—3, Fig. 1, and Fig. 4 a section along the line 4—4, Fig. 1.

The reference numeral 2 designates the hollow cylinder which is closed at its ends by means of heads 3 and 4. The cylinder has at diametrically opposite points intermediate of its ends, an admission port 5 and an exhaust port 6, respectively connected with conduits 7 and 8 for the flow of motive fluid to and from the same.

The head 3 has a centrally disposed stuffing box 9 of conventional construction for the sliding passage of a piston-rod 10 which at its inner end is by means of a key

12 rigidly connected with a piston 13 which is slidably fitted in the cylinder.

The piston which at its opposite ends, carries packing rings 14 to effect a fluid tight connection with the interior surface of the cylinder, has between its said ends, diametrically opposite, longitudinally extending open recesses 15 and 16 which serve as chambers for the inlet valve and the exhaust valve which are mounted on the piston as will hereinafter be described.

The inlet chamber 15 connects with the portions of the cylinder at opposite ends of the piston by axially aligned passages 17 formed in its end walls, and these passages are provided with screw threads to receive 70 co-operatively threaded screw plugs 18 in which the valve is longitudinally slidably supported, as will hereinafter be described.

The plugs have central bores for the support of the valve, surrounded by openings 75 19 which provide ducts for the passage of motive fluid from the valve chamber to the portions of the cylinder at the respective ends of the piston, and at their inner ends they have concentric valve seats which in 80 the operation of the engine are alternately engaged by correspondingly ground faces on the valve to close the passages occupied by the plugs on which they are formed.

The valve consists of an oblong body comprising two heads 21 which are integrally connected by a tapering shank 20 of reduced diameter, and which at their outer ends are chamfered to fit the seats on the inner ends of the plugs 18.

The valve body is provided at its extremities with axially aligned stems 22 of reduced diameter which are slidably fitted in the axial bores of the screw plugs and project beyond the ends of the piston.

Inasmuch as the distance between the chamfered faces of the valve body is less than that between the seats on the plugs, the valve has a limited longitudinal movement in its chamber, which may be varied 100 by adjustment of the plugs and which in the operation of the engine is obtained by the abutment of the ends of the valve stems 22 with the inner end surfaces of the cylinder.

A curved leaf-spring 23 applied between 105 the shank of the valve and the bottom surface of the chamber 15, serves to frictionally maintain the valve in its adjusted positions.

The exhaust chamber 16 of the piston has like the intake chamber, axially aligned passages 24 in its end walls to establish communication between its interior and the portions of the cylinder at opposite ends of the piston.

The exhaust valve which occupies the chamber, consists of a hollow cylindrical body 25 which is slidably fitted in the passages 24 and which is closed at its ends by means of valve disks 26 of greater diameter which are rigidly connected and held in place on the body by nuts 27 screwed on the threaded ends of a bolt 28 which projects through central apertures of the disks. The inner faces of the valve members are chamfered to fit seats provided by countersinking the outer edges of the respective passages in the end walls of the chamber.

20 The length of the body portion of the exhaust valve exceeds that of the piston to permit of a limited longitudinal movement of the valve to alternately close the passages 24, which movement is like that of the intake 25 valve, obtained by the engagement of the extremities of the valve 25, in this case the ends of the bolt 28, with the inner surfaces of the cylinder heads.

30 The hollow body portion of the valve has adjacent its ends, longitudinally extending oblong ports 29 which when the disks 26 are separated from their respective seats open the passages 24, for the flow of motive fluid from the interior of the cylinder into the chamber 16.

35 A spring 30 disposed in the bottom of the exhaust chamber, engages the cylindrical body 25 to frictionally maintain the valve in its adjusted positions.

40 The length of the piston 3 exceeds one-half the interior length of the cylinder, so that when the piston is at the end of its strokes, it covers the admission port and the exhaust port in the peripheral wall of the 45 cylinder, which ports are thus in continuous communication with the open sides of the valve chambers 15 and 16, in the periphery of the piston.

50 When the piston is at the end of its outward stroke as shown in Fig. 1 of the drawings, the ends of the stem 22 of the intake valve and the bolt 28 of the exhaust valve, at the outer end of the piston, engage the inner surface of the outer head of the cylinder, 55 with the result that the passage 17 of the intake chamber at the said end of the piston, is open and the passage 24 of the exhaust chamber at the same end of the piston is closed.

60 The motive fluid entering the cylinder through the port 5, flows into the intake chamber and through the open ducts 19 of the plug 18 at the forward end of the piston, into the space between the said end and the head 4 of the cylinder, and by its expansive

force, drives the piston inwardly until the ends of the stem on the intake valve and the bolt on the exhaust valve at the opposite end of the piston, engage the inner head 3 of the cylinder when the position of the 70 two valves is automatically reversed.

The intake valve being shifted to close the passage at the outer end of its chamber by engagement with the seat of the respective screw plug, at the same time opens the 75 passage at the opposite end of the same, thereby permitting the fluid entering the cylinder through the port 5, to flow from the intake chamber of the piston which is in constant communication with said port, through 80 the open passage, into the space between the piston and the head 3 of the cylinder, to drive the piston outwardly. The spent fluid at the opposite end of the piston is at the same time compelled to enter the exhaust 85 chamber through its open passage 24 at the forward end of the piston with relation to the direction of its movement, and is exhausted from the said chamber through the port 6 in the cylinder wall, with which its 90 open side is in constant communication. It will thus be seen that by the reciprocating movement of the piston, the positions of the two valves mounted therein are automatically reversed at the end of each stroke, 95 whereby the motive fluid is admitted in the cylinder alternately at opposite ends of the piston and the spent fluid is simultaneously exhausted from the interior of the cylinder at the other end of the same. 100

To reverse the direction of rotation of a shaft with which the piston-rod has a driving connection, I have provided a simple contrivance which enables the engineer to reverse the positions of the valves on the 105 piston at any point in its reciprocating movement. This contrivance consists of two flat abutment plates 31 which normally are disposed in correspondingly formed recesses 32 in the inner surfaces of the cylinder- 110 heads and which are rigidly attached at the ends of rods 33 which pass slidably through stuffing boxes 34 on the said heads.

To reverse the valves on the piston for the purpose of reversing the direction of rotation of the engine shaft, it is but necessary to move one of the plates 31 inwardly, as shown at the left-hand side of Fig. 1, until it is engaged by the ends of the valves, it being understood that levers or other suitable devices are connected with the rods for their operation. 115

It will be observed that at the end of the piston forward with relation to the direction of its movement, the end of the exhaust 120 valve is slightly in advance of the end of the stem on the intake valve so that the exhaust of motive fluid will be discontinued before a fresh charge of fluid is admitted.

Pet-cocks 35 are applied at the bottom of 125

the cylinder for the drainage of water of condensation, it being understood however, that air under pressure is as effective a medium for the operation of the engine, as 5 steam.

Having thus described my invention what I claim and desire to secure by Letters-Patent is:

1. In an engine of the character described, 10 a cylinder having an admission port and an exhaust port intermediate of its ends and abutments adjacent its said ends, a reciprocating piston having chambers opening in its circumferential surface to register with said port, and passages for establishing communication between said chambers and the portions of the cylinder at opposite ends of the piston, and valves shiftably mounted on said piston to alternately 15 open and close the said passages of its said chambers, by engagement with said abutments.

2. In an engine of the character described, 20 a cylinder having intermediate of its ends an admission port and an exhaust port, and adjacent its ends, abutments, a reciprocating piston having valve-chambers disposed to register with the respective ports, and passages for establishing communication between 25 said chambers and the portions of the cylinder at opposite ends of the piston, and valves shiftably mounted on the piston to alternately close and open the said passages of its said chambers by engagement with 30 said abutments, the said abutments being adjustable to be operatively positioned at different selected points in the path of the piston.

3. In an engine of the character described, 35 a cylinder having intermediate of its ends an admission port and an exhaust port, and adjacent its ends, abutments, a reciprocating piston having valve-chambers disposed to register with the respective 40 ports, and passages for establishing communication between said chambers and the portions of the cylinder at opposite ends of the piston, and valves shiftably mounted on the piston to alternately close and open the said passages of its said chambers by engagement with 45 said abutments, one of the

said abutments being adjustable to be operatively positioned at different selected points in the path of the piston.

4. In an engine of the character described, 55 a cylinder having a port intermediate of its ends and abutments adjacent its said ends, a reciprocating piston having a chamber opening in its circumferential surface to register with said port, and passages for establishing communication between said chamber and the portions of the cylinder at opposite ends of the piston, and a valve mounted on said piston to alternately open and close said passages by engagement with 60 65 said abutments.

5. In an engine of the character described, 70 a cylinder having a port intermediate of its ends and abutments adjacent its said ends, a reciprocating piston having a chamber 75 opening in its circumferential surface to register with said port, and passages for establishing communication between said chamber and the portions of the cylinder at opposite ends of the piston, a valve mounted on said piston to alternately open and close said passages by engagement with said abutments, and means on said piston for frictionally maintaining said valve in its adjusted positions. 80

6. In an engine of the character described, 85 a cylinder having an admission port and an exhaust port intermediate of its ends, and abutments adjacent its said ends, a reciprocating piston having chambers and in its circumferential surface openings connected with said chambers and adapted to continuously register with the respective ports during movement of the piston, and 90 passages for establishing communication between said chambers and the portions of the cylinder at opposite ends of the piston, and valves shiftably mounted on said piston to alternately open and close the said passages of its said chambers, by engagement with 95 said abutments.

In testimony whereof I have affixed my signature in presence of two witnesses.

CHRIS LARSON.
